UNITED STATES PATENT OFFICE.

VIRGIL BALLOU, OF OSKALOOSA, IOWA.

FURNACE.

1,297,056.

Specification of Letters Patent. Patented Mar. 11, 1919.

Application filed September 17, 1917. Serial No. 191,883.

To all whom it may concern:

Be it known that I, VIRGIL BALLOU, a citizen of the United States, and resident of Oskaloosa, in the county of Mahaska and State of Iowa, have invented a certain new and useful Furnace, of which the following is a specification.

My invention relates to furnaces of the hot water or steam heating type.

10 The object of my invention is to provide a furnace of the general type mentioned, having an arrangement of water boiler and fire box, with means for conducting air to the fire box and through the boiler for giving a maximum of heat to the boiler and for securing a complete combustion of fuel.

15 Other objects will appear throughout the following specification.

With the above and other objects in view, 20 my invention consists in the construction, arrangement and combination of the various parts of the device, whereby the objects contemplated are attained, as hereinafter more fully set forth, pointed out in my claims, 25 and illustrated in the accompanying drawings, in which:

Figure I shows a front elevation of a furnace embodying my invention, parts being broken away and parts being shown in section.

30 Fig. II shows a horizontal, sectional view, taken on the line 2—2 of Fig. IV.

Fig. III shows a horizontal, sectional view, taken on the line 3—3 of Fig. IV, 35 parts being broken away to show the water conducting pipes.

Fig. IV shows a fore and aft vertical, sectional view through the device, parts being broken away and part of the boiler being 40 shown in side elevation, and

Fig. V shows a transverse, vertical, sectional view, taken on the line 5—5 of Fig. IV.

In the accompanying drawings I have 45 used the reference numeral 10 to indicate generally the outer casing of my improved furnace, which may be made of brick or any other suitable material. At the rear of the furnace is an ordinary flue or chimney 11.

50 The furnace is provided in its lower portion with a suitable fire box 12 of any suitable construction. Below the fire box 12 is an ash pit 13.

The front wall of the furnace is provided 55 with a clean-out door 14 for permitting access to the ash pit 13, and with a lower

draft door 15 hinged at its upper edge for permitting access to the fire box 12.

Located on the interior of the furnace above the fire box 12, is a drum-shaped 60 boiler 16, the central portion of which is open, as illustrated in Figs. II and III, at 17. Above the boiler 16 is a water reservoir 18, which communicates with the boiler 16, as 65 illustrated in Fig. V.

Extending from the lower end of the boiler 16 to the upper end thereof are spaced boiler flues or tubes 19, which are preferably inclined from their lower ends upwardly and outwardly, as illustrated in 70 Fig. V. Water pipes 20 and 21 extend through the front wall of the furnace and communicate with the boiler 16. Leading from the reservoir 18 may be a steam discharge pipe 22.

75 In the upper front portion of the wall 10 is an inwardly leading passage 23 which registers with a passage 24 leading through the wall of the boiler 16, as illustrated in Fig. IV, to the open central portion 17 of 80 the boiler.

In the upper front portion of the furnace 85 is a passage 25 leading laterally, thence downwardly to the passage 23. For closing the outer end of the passage 25 there is provided an upper draft door 26, shown in Fig. I.

Surrounding the upper portion of the boiler 16 is a baffle plate 27, having in its rear part an opening 28. Spaced below the 90 baffle plate 27 is a second baffle plate 29, which has at its forward end an opening 30. The rear wall of the furnace is provided with an opening 31 leading from the space 95 below the lower baffle plate 29 to the chimney or flue 11.

Suitably located just above the baffle plate 27 are clean-out passages 32 which are closed by doors 33. Just above the baffle plate 29 are similar clean-out passages, at the outer 100 ends of which are similar doors 34. The wall of the furnace is provided with additional passages, similar to the passages 32, leading to the space or compartment below the baffle plate 29 and closed at their outer 105 ends by doors 35 similar to the doors 33 and 34.

Suitably mounted on the furnace is a pressure motor device 36 for operating a lever arm 37. Secured to the lever 37 near 110 its outer end, is a chain 38 connected with the upper draft door 26. On the lever 37

is slidably mounted the weight 44. Connected with the lever arm 37 at a point nearer the pressure motor is another chain 39 connected with the lower draft door 15. It will be noted that the lever arm 37 is pivoted to a bracket 40 adjacent to the pressure motor device 36, which is connected with the boiler and is responsive to the steam pressure therein, so that when the steam pressure goes down the draft doors are opened, and when the steam pressure is high the draft doors are moved toward closed position for automatically regulating the draft.

15 In the practical use of my improved furnace it will be understood that the boiler is connected with a suitable source of water supply, and that fuel is supplied to the fire box 12 through the passage 23, the outer end 20 of which is closed by the door 41.

When the draft door 26 is opened, air will pass in the direction indicated by the arrows in Fig. I, through the passage 25 to the passage 23, shown in Fig. IV, leading to 25 the interior compartment 17 of the boiler, and thence downwardly to the upper part of the fuel in the combustion chamber. Under many circumstances the draft door 26 furnishes substantially all the fresh air 30 needed, but where more fresh air is needed it can be furnished through the lower draft door 15 and the passage 42 leading to the fire box.

The smoke and products of combustion 35 and heated air pass upwardly through the tubes 19 to a space 43, and thence around the reservoir 18 to the rear of the furnace, and thence downwardly through the opening 28 to the compartment between the baffle 40 plates, thence around the boiler 16 to the forward portion of the furnace, and thence downwardly through the opening 30 in the lower baffle plate 29, and thence once more 45 around the boiler and through the passage 31 to the chimney 11. The arrangement of the air passages and the passages for smoke and products of combustion is such as to furnish a thorough and complete combustion 50 of fuel in the fire box 12, and to furnish maximum heat to the boiler 16.

It will be noted that the pressure motor device is arranged with the chain 38 secured near the outer end of the lever 37. The said outer end has a greater range of movement 55 than that portion of the lever 37 to which the chain 39 is secured. The parts are so arranged that the pressure motor normally holds the lever 37 raised, which would hold the upper draft door fully open and the lower draft door partly open. When the pressure motor is operated to lower the lever

37, the lower draft door will close first, so that ordinarily during the operation of the furnace all, or the greater portion, of the fresh air is supplied through the upper 65 draft door. When the fire is first started, however, and a greater draft is needed, such draft is supplied through both the draft doors.

It will be noticed that the passage 25 is 70 in the wall of the furnace and is spaced from the boiler until it communicates with the passage 24 which leads directly through the boiler.

Some changes may be made in the construction and arrangement of the various parts of my improved furnace without departing from the essential features and purposes of my invention, and it is my intention to cover by the patent to be issued on 80 my present application, any modified forms of structure or use of mechanical equivalents which may be reasonably included within the scope of my claims.

I claim as my invention:

1. In a furnace, a fire box, a double walled boiler having a central portion forming a discharge chamber for the fire box, said furnace having a comparatively thick wall, a passage in said wall leading downward 90 from the upper portion thereof, provided with an air inlet and spaced from the boiler, a passage communicating with said passage and leading directly through the boiler wall substantially on a horizontal 95 line and adapted to supply air to the upper portion of the fuel, and a third passage leading through the wall of the furnace to the fire box for supplying air to the fire box just above the lower part thereof.

2. In a furnace, a fire box, a double walled boiler having a central portion forming a discharge chamber for the fire box, said furnace having a comparatively thick wall, a passage in said wall leading downward 105 from the upper portion thereof, provided with an air inlet and spaced from the boiler, a passage communicating with said passage and leading directly through the boiler wall substantially on a horizontal line and adapted to supply air to the upper portion 110 of the fuel, a third passage leading through the wall of the furnace to the fire box for supplying air to the fire box just above the lower part thereof, doors for controlling 115 the admission of air to said first and last described passages, a pressure motor device adapted to simultaneously control said doors, and adapted to open the lower door last and to close it first.

Des Moines, Iowa, August 16, 1917.

VIRGIL BALLOU.
